CONCRETE CURB CONSTRUCTION

Original Filed Aug. 21, 1919

FIG. I.

FIG. II.

FIG. III

FIG. IV.

FIG V

INVENTOR:

INVENTION.
Harry Edgar Dillon,
by Arthur E. Paige,
Inventor.

UNITED STATES PATENT OFFICE.

HARRY EDGAR DILLON, OF PHILADELPHIA, PENNSYLVANIA.

CONCRETE CURB CONSTRUCTION.

Application filed August 21, 1919, Serial No. 318,885. Renewed March 22, 1924.

To all whom it may concern:

Be it known that I, HARRY EDGAR DILLON, a citizen of the United States, residing at Philadelphia, in the county of Philadelphia and State of Pennsylvania, have invented a certain new and useful Improvement in Concrete Curb Construction, whereof the following is a specification, reference being had to the accompanying drawing.

10 My invention relates to curb structures formed of sections which may be precast or molded remote from the regions in which they are to be assembled, and it is the object and effect of my invention to provide 15 means for conveniently and rigidly assembling them in monolithic relation.

As hereinafter described, my invention includes the provision of curb sections with stepped ends adapted to overlap, and tubular metallic reinforcing members imbedded in one of said sections and fitted to corresponding sockets in the complementary end of another section; said reinforcing members serving as conduits adapted to convey 25 cementing means to an interior cavity, between said sections, formed by complementary recesses in the respective sections, so that when concrete or other suitable cementing medium is poured in said reinforcing 30 members to fill said recess, the curb sections are permanently interlocked, in monolithic relation, when such cementing medium sets.

An adjunctive feature of my invention is the provision in such curb sections of means 35 to interlock with a gutter slab; so that the gutter line is conveniently predetermined by the location of such curb sections.

My invention includes the various novel features of construction and arrangement 40 hereinafter more definitely specified.

In the drawing: Fig. I is an elevation of a series of precast or molded curb sections conveniently embodying my invention; one of the intermediate sections including the 45 means above contemplated for interlocking with a gutter slab. Fig. II is a transverse sectional view of said structure taken on the line II, II in Fig. I. Fig. III is a transverse sectional view of said intermediate section, taken on the line III, III in Fig. I, and showing a gutter slab interlocked with said section. Fig. IV is a perspective view of one of the vertical reinforcing members indicated in Figs. I and II. Fig. V is a perspective view of one of the horizontal reinforcing members indi-

cated in Figs. I and II. Fig. VI is a fragmentary plan sectional view taken on the line VI, VI in Figs. I and II, showing means permitting limited longitudinal movement of the connected sections of the structure to allow for expansion thereof.

Referring to Fig. I; each of the curb sections 1, 1, may be precast or molded of the same pattern with its oppositely stepped ends 2 and 3, complementary to each other; so that a longitudinal series of such sections may be fitted together to form a continuous curb of uniform cross section. Each of such sections has its stepped end 2 provided with two vertical tubular metallic reinforcements 5, which may be cast therein in the spaced relation indicated in Fig. II, and depending below said member 2 in position to fit in corresponding sockets 6 in the complementary stepped end 3 of the adjoining section. Each of said reinforcing elements 5 has a vent 8 opening from its interior into the recess 9 in the under face of said stepped member 2 of said section, which recess 9 is complementary to the recess 10 in the upper face of the stepped member 3 of said section; so that when the sections are fitted together as shown in Fig. II, said complementary recesses 9 and 10 form a cavity 11 which may be filled with liquid concrete or other suitable cementing medium 12 conducted thereto by pouring the same into said tubular reinforcing members 5; so that, when said cementing medium has set, said sections are interlocked thereby in the relation shown in Figs. I and II. One or more metallic reinforcing members 13 may be rigidly mounted in each section 1, so as to project horizontally in said cavity 11 and the cement block therein.

Moreover, I prefer to form said cavity 11 with an extension 14, indicated in dotted lines in Fig. I, by providing complementary recesses 15 and 16 in the vertical end faces 100 of said sections 1 respectively below said stepped member 2 at the inner end thereof, and at the outer end of said stepped member 3.

It may be observed that the body of cementing material in the cavity 11 reinforces the joint between said sections 1 against transverse shearing stresses, and that the body of cementing material in said cavity extension 14 reinforces the joint between 110 said sections against torsional stresses such as are imposed upon adjoining sections 1

by the effects of frost in the material in which said sections are imbedded. Of course, the tubular members 5 are opposed to all such stresses.

- 5 As shown in Fig. VI, said sockets 6 substantially fit the reinforcing members 5 laterally, so as to maintain the adjoining sections in alinement, but said sockets 6 are of greater extent than said members 5 longitudinally, so that limited longitudinal movement of the adjacent sections incident to expansion, may be permitted, by using a cementing material which remains plastic. However, as shown in Fig. VI, said members 5 are so grouped as to prevent relative rotary displacement of the two nonmetallic bodies 1 which they thus connect, and that effect is attainable with even two reinforcing members thus fitted in sockets which are 10 of different extent in transverse directions, as shown in said figures; but is not attained if but a single reinforcing member 5 be arranged as shown in said figure; although such single reinforcing member 20 would suffice to prevent lateral displacement of said bodies with respect to each other while permitting longitudinal displacement to a limited extent.

I prefer to make said cavity 11 rectangular in vertical cross section, as indicated in Fig. II; but said extension 14 of said cavity may be cylindrical in horizontal cross section; or either may be otherwise shaped.

Of course, such joints as above described 35 may be used to connect complementary members of curb sections which are not otherwise constructed or arranged like said sections 1. For instance, precast or molded curb sections 18 may have stepped members 40 2 at both ends; and the curb sections 19 may have stepped members 3 at both ends, and joints be made between the overlapped members 2 and 3, in the same manner above described with reference to the sections 1.

45 As indicated in Fig. I, said curb sections may be provided with recesses 21 for engagement with gutter slabs 23, one of which is shown engaged in Fig. III. As indicated in Figs. I and III; said section 1 may have reinforcing bars 24 with eyes 25 extending in said recesses 21 in position to engage the hooked ends 27 of the reinforcing bars 28 set in said slabs 23. It is to be understood that said gutter slabs 23 may be united 50 in monolithic relation with said curb sections 1 by cementing material 30 poured into said recesses 21. Moreover, the joints between such curb sections may be thus bridged, and reinforced, by such gutter slabs.

60 Although I prefer to provide the upper corner of the gutter side of the curb aforesaid with a metallic reinforcing member 32, forming a nosing, rigidly connected with the plastic body of the curb sections by inward 65 extensions 34 which are preferably foram-

inous as indicated in Fig. III; that feature of the structure illustrated is not of the essence of the invention herein claimed.

Although I have outlined, in Fig. III, the curb section 1 as wider at the base than at 70 the top, as is usual in stone curbs, and such configuration has the advantage of greater stability than if the curb were of the same width at the bottom as at the top; such details of configuration are not of the essence 75 of my invention.

Therefore, I do not desire to limit myself to the precise details of construction and arrangement herein set forth, as it is obvious that various modifications may be made 80 therein, without departing from the essential features of my invention, as defined in the appended claims.

I claim:

1. In a curb structure, the combination 85 with a plurality of nonmetallic bodies each forming a unit section of said structure, with stepped, complementary ends having complementary recesses, adapted to form an internal cavity in said structure; of a tubular 90 metallic reinforcing member extending from one section into another and having a vent opening into said cavity; a bonding element including cementing material poured into said cavity through said tubular reinforcing 95 element; whereby the opposite ends of similar sections are interengaged by said tubular members, and are united by said cementing medium; a pair of gutter slab recesses, in the gutter side of the adjoining 100 curb sections; a gutter slab, bridging adjoining sections and having members fitted to gutter slab recesses in each; and a bonding element, including cementing material in said gutter slab recesses; whereby said gutter 105 slab is united in monolithic relation with adjoining curb sections and bridges the joint between them.

2. In a curb structure, the combination 110 with a plastic body, with stepped, complementary, longitudinally projecting members respectively at the upper and lower regions thereof; having complementary recesses, respectively in the lower horizontal face of the upper step member and in the upper horizontal face of the lower step member, and having complementary recesses in vertical faces of said body, respectively at the inner end of said upper step member and at the outer end of said lower step member, and with a pair of sockets extending vertically in said lower step member; of a pair of tubular metallic reinforcing members rigidly mounted vertically in said upper step member, upon respectively opposite sides of the recess in said member and projecting below the latter, but terminating above the bottom of said body, in the same transversely spaced relation as said sockets, and each having a vent opening into said recess and forming a 115 120 125 130

conduit for cementing material; a pair of metallic reinforcing members rigidly mounted horizontally in said body, so as to project in said recess, between said vertically reinforcing members; whereby opposite ends of such sections are fitted to overlap and to interengage by said tubular extension, and be united by a cementing medium.

3. In a curb structure, the combination with 19 a plastic body, with stepped, complementary, longitudinally projecting members respectively at the upper and lower regions thereof; having complementary recesses, respectively in the lower horizontal face of the upper step member and in the upper horizontal face of the lower step member, and having complementary recesses in vertical faces of said body, respectively at the inner end of said upper step member and at the outer end 20 of said lower step member, and with a pair of sockets extending vertically in said lower step member; of a pair of tubular metallic reinforcing members rigidly mounted vertically in said upper step member, upon respectively opposite sides of the recess in said member and projecting below the latter, but terminating above the bottom of said body, in the same transversely spaced relation as said sockets, and each having a vent opening 25 into said recess and forming a conduit for cementing material; whereby opposite ends of such sections are fitted to overlap and to interengage by said tubular extension, and be united by a cementing medium.

35 4. In a curb structure, the combination with a plastic body, with stepped, complementary, longitudinally projecting members respectively at the upper and lower regions thereof, having complementary recesses, respectively in the lower horizontal face of the upper step member and in the upper horizontal face of the lower step member, and having complementary recesses in vertical faces of said body, respectively at the inner 40 end of said upper step member and at the outer end of said lower step member, and with a socket extending vertically in said lower step member; of a tubular metallic reinforcing member rigidly mounted vertically in said upper step member and projecting below the latter, but terminating above the bottom of said body, and having a vent opening 45 into said recess and forming a conduit for cementing material; a metallic reinforcing member rigidly mounted horizontally in said body, so as to project in said recess; whereby opposite ends of such sections are fitted to overlap and to interengage by said tubular extension, and be united by a cement- 50 ing medium.

55 5. In a curb structure, the combination with a plastic body, with stepped, complementary, longitudinally projecting members respectively at the upper and lower regions thereof, having complementary recesses, re-

spectively in the lower horizontal face of the upper step member and in the upper horizontal face of the lower step member, and having complementary recesses in vertical faces of said body, respectively at the inner 70 end of said upper step member and at the outer end of said lower step member, and with a socket extending vertically in said lower step member; of a tubular metallic reinforcing member rigidly mounted vertically in 75 said upper step member and projecting below the latter, but terminating above the bottom of said body, and having a vent opening into said recess and forming a conduit for cementing material; whereby opposite 80 ends of such sections are fitted to overlap and to interengage by said tubular extension, and be united by a cementing medium.

6. In a curb structure, the combination 85 with two nonmetallic bodies having complementary recesses in registry with each other forming a cavity between said bodies; each of said bodies having a metallic reinforcing bar imbedded therein and extending 90 freely in said recess parallel with the junction between said bodies; each of said bodies having two sockets, respectively upon transversely opposite sides of said reinforcing bars; said sockets being in registry in the 95 respective bodies; a pair of tubular metallic reinforcing members extending in said sockets from one of said bodies to the other, bridging the joint between them, and each 100 having an opening from its interior into said cavity; and a cementing medium extending through each of said tubular reinforcing members into said cavity; whereby 105 said four reinforcing members are interlocked with said cementing medium and said two bodies inseparably connected.

7. In a curb structure, the combination 110 with two nonmetallic bodies, each having a recess and fitted together with said recesses in complementary relation forming a cavity between said bodies; of reinforcing bars respectively imbedded in each of said bodies and extending in said recesses; a tubular reinforcing member extending in each of said bodies across said cavity, transversely to said bars, and having an opening from its interior into said cavity; and a cementing medium extending through said tubular reinforcing member into said cavity; whereby 115 said four reinforcing members are interlocked with said cementing medium and said two bodies inseparably connected.

8. In a curb structure, the combination 120 with two nonmetallic bodies overlapping each other and each having a recess in complementary relation to a recess in the other body, forming a cavity between said body; of a tubular reinforcing member extending from one of said bodies to the other, across 125 said cavity, and having an opening from its 130

interior into said cavity; said reinforcing member being wholly within said structure; and a cementing medium extending through said reinforcing member into said cavity; whereby said reinforcing member is interlocked with said cementing medium and said two bodies inseparably connected.

9. In a curb structure, the combination with two nonmetallic bodies in overlapped relation, each having a recess complementary to a recess in the other body and in registry therewith, forming a cavity between said bodies; of a metallic reinforcing member imbedded in each of said bodies and extending in spaced relation in said cavity, parallel with the joint between said bodies; one of said bodies having a socket leading from its exterior to said cavity; and a cementing medium extending through said socket into said cavity; whereby said bodies are interlocked.

10. In a curb structure, the combination with two nonmetallic bodies in overlapped relation, each having a recess complementary to a recess in the other body and in registry therewith, forming a cavity between said bodies; one of said bodies having a socket leading from its exterior to said cavity; and a cementing medium extending through said socket into said cavity; whereby said bodies are interlocked.

11. In a curb structure, the combination with two nonmetallic bodies in overlapped relation, each having two sockets extending transversely to the joint between said bodies and wider in the direction of the length of said joint than transversely to such length; said sockets in one body being in registry with the sockets in the other body; tubular reinforcing members extending in said sockets, bridging said joint, substantially fitting said sockets transversely but in

spaced relation with said sockets longitudinally with respect to said joint; each of said tubes having an opening from its interior into the socket in which it extends; and a plastic cementing medium extending through said tubes into their respective sockets; whereby said bodies are prevented from displacement transversely with respect to said joint but are free for limited displacement longitudinally with respect to said joint; the plurality of said reinforcing members being so grouped as to prevent rotary movement of said bodies with respect to each other.

12. In a curb structure, the combination with two nonmetallic bodies in overlapped relation, each having a socket extending transversely to the joint between said bodies and wider in the direction of the length of said joint than transversely to such length; said sockets being in registry with each other; a tubular reinforcing member extending in said sockets, bridging said joint, substantially fitting said sockets transversely but in spaced relation with said sockets longitudinally with respect to said joint; said tube having an opening from its interior into said sockets; and a plastic cementing medium extending through said tube into said socket; whereby said bodies are prevented from displacement transversely with respect to said joint but are free for limited displacement longitudinally with respect to said joint.

In testimony whereof, I have hereunto signed my name at Philadelphia, Pennsylvania, this eighteenth day of August, 1919.

HARRY EDGAR DILLON.
